DICTATING MACHINE CYLINDER
VACUUM CLEANER

Gustave Miller, New Haven, Conn.

Application June 13, 1933, Serial No. 675,625

7 Claims. (Cl. 274—47)

(Granted under the act of March 3, 1883, as
amended April 30, 1928; 370 O. G. 757)

This invention relates to dictating machine cylinder vacuum cleaner and has for an object to provide an improved cleaning mechanism for removing the fuzz on a dictating machine cylinder as it is created during the process of dictating to the machine.

A further object of this invention is to provide an improved cleaning mechanism for the blank or cylinder of a recording or dictating machine which operates simultaneously with the process of dictating to the machine.

A further object of this invention is to provide a cleaner for a dictating cylinder which serves to continuously eliminate the fuzz produced by the dictating stylus on the dictating cylinder.

A further object of this invention is to provide a vacuum cleaner for the cylinder of the dictating machine which serves to continuously remove the fuzz produced by the dictating stylus on the cylinder and which does not need any additional motive power over that already provided in the dictating machine.

A further object of this invention is to provide a vacuum cleaner for the cylinder of the dictating machine wherein pressure normally created by the dictating machine is utilized to create a vacuum and withdraw the fuzz from the cylinder and deposit it in a suitable receptacle.

With the above and other objects in view, the invention consists in the construction, combination and arrangement of parts as will be hereinafter more fully described.

Reference is to be had to the accompanying drawing forming a part of this specification in which like reference characters indicate corresponding parts throughout the several views and in which:

Fig. 1 is a partly elevational and partly sectional view of a dictating machine to which this invention has been applied;

Fig. 2 is a sectional view partly broken away on line 2—2 of Fig. 1; and

Fig. 3 is a schematic outline of the application of this invention.

There is shown at 10 a schematic representation of a dictating machine, this dictating machine being of the type commercially known as the Dictaphone, the Ediphone, or other similar types of recording or dictating machines. The 50 dictating machine 10 has the usual operating motor 11 placed within the base 12 and connected by a belt 13 to a pulley on a shaft 14 which operates within the boss 15 to control the rotation of the recording blank or dictating cylinder 16 in the usual manner. A stylus plate 17 is

actuated over the surface of the dictating cylinder 16 in the usual manner and has a talking tube 18 for activating the dictating stylus point 19. As the stylus point 19 is actuated over the dictating cylinder 16 by the vibrations of the sound through the talking tube 18 the stylus point 19 produces a fuzz or minute shavings from the surface of the dictating cylinder 16 as it records the sound vibrations therein. All of the aforesaid mechanism is conventional and well known and found in the commercial dictating machines above referred to and form no part of this invention per se.

Projecting from the motor 11 in the base 12 is a shaft 20 provided with a series of fan blades 21. In one of the above types of machine these fan blades 21 are already present for the purpose of cooling a control coil (not shown) which is used in connection with the mechanism, but if such is not already present this shaft 20 and blades 21 are necessarily provided. The blades 21 during the operation of the motor 11 provide a current of air part of which is collected in the cone-shaped receiver 22 to provide a pressure passing through the pipe 23 to a removable container 24, the container 24 being at least partially perforated to allow the pressure to escape therefrom. The pipe 23 is provided with a restriction 25 at which point a joining pipe 26 is secured thereto. The other end of this joining pipe 26, 30 which will be of rubber or other suitable flexible material, terminates in a wide flattened mouth or nozzle 27, which is secured to the bottom of the stylus plate 17 so that the opening is closely adjacent the stylus point 19. In operation the 35 motor 11 is always necessarily operated while dictation is taking place. The fan blades 21 create a pressure through the pipe 23, which pressure is increased by means of the restriction 25 projecting therein. According to well-known 40 laws of physics, the air rushing past the end of the restriction 25 creates a vacuum behind this restriction 25, at which point the end of the pipe 26 is joined, thus creating a vacuum in the pipe 26. The vacuum in the pipe 26 is relieved by air 45 entering the wide flattened mouth or nozzle 27, and inasmuch as this air is drawn from the immediate vicinity of the stylus point 19, it carries with it the fuzz or shavings created by the stylus point 19 on the surface of the dictating cylinder 16 and removes this fuzz or shavings through the pipe 26 and the pipe 23 into the container 24.

Container 24 may be emptied from time to time as may be necessary. In this manner the 55

annoyance caused by the collection of the shavings or fuzz is eliminated and the surface of the dictating cylinder 16 remains clean and free of these shavings or fuzz and hence the clarity of 5 the dictation is not interferred with through the accumulation of these shavings or fuzz beneath the stylus point.

It will be understood that the above description and accompanying drawing comprehend 10 only the general and preferred embodiment of my invention and that various changes in construction, proportion and arrangement of parts may be made within the scope of the appended 15 claims without sacrificing any of the advantages of my invention.

The invention described herein may be manufactured and used by or for the Government of the United States of America for governmental purposes without the payment of any royalties 20 thereon or therefor.

I claim:

1. In a device which records by engraving a surface of a record, the combination of a stylus having a point adapted to engrave a surface of 25 a recording blank; means including an electric motor and shaft for relatively moving said stylus and blank so that the stylus point may range over a surface of the blank; a blank shavings-receptacle formed at least in part of a previous 30 wall adapted to permit air flow through such wall; a pipe leading from adjacent said motor to said receptacle; a fan mounted on the motor shaft intermediate and juxtaposed to the motor and an end of the pipe, whereby the fan in 35 operation moves air from adjacent the motor into the pipe; and a branch pipe having one of its ends adjacent the stylus point and its remaining end leading at an angle and joined to the pipe for drawing record shavings from the stylus 40 point into the pipe through which the shavings are moved into the receptacle.

2. The combination of claim 1 characterized by means at the juncture of the pipe and branch pipe for moving record shavings-laden air into 45 the branch pipe and thence into the receptacle

by the force of motor cooling air driven by the fan into the pipe.

3. The combination of claim 1 characterized by the branch pipe being joined to the pipe by projecting thereinto in the direction of air flow 5 in the pipe around said projection for moving record shavings-laden air from the stylus point into the pipe and thence into the receptacle by the force of motor cooling air driven by the fan into the pipe. 10

4. The combination of claim 1 characterized by the end of the branch pipe adjacent the stylus point being flared.

5. The combination of claim 1 characterized by the end of the pipe adjacent the fan having 15 a funnel converging away from the outlet of the fan and into the pipe.

6. In a device which records by engraving a surface of a record, the combination of a stylus having a point adapted to engrave a surface of 20 a recording blank; means including a motor having a shaft for relatively moving the stylus and blank so that the stylus point may range over a surface of the blank, and a fan mounted 25 on and revoluble with the motor shaft adjacent one end of the motor for cooling the motor by increasing the air flow from the motor when the fan is running, with a record shavings receptacle, and means for collecting the record 30 shavings from the stylus point and depositing them in the shavings receptacle by the force of air moved by said fan.

7. In a device which records by engraving a surface of a record, the combination of a stylus having a point adapted to engrave a surface of a recording blank; a fan, means for driving the fan and relatively moving the stylus and blank; a recording blank shavings receptacle; a pipe having one end adjacent and receiving air from the fan and its other end connected to the receptacle; a branch pipe having one end adjacent the stylus point and its other end entering the side of the pipe and extending slightly toward the receptacle. 35 40 45
